CLAIM

A new, original, ornamental design for a ski glasses, as shown and described.

DESCRIPTION

FIG. 1 is a first perspective view of a ski glasses showing my new design;

FIG. 2 is a second perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof; and,

FIG. 9 is a perspective view showing the ski glasses in a state of use.
The broken lines in FIG. 9 illustrate a head of a user and a belt which form no part of the claimed design.**1 Claim, 9 Drawing Sheets**(56)
